MASK FOR STRIPING WHEELS

Fred A. Neuman, Lansing, Mich., assignor to
General Motors Corporation, Detroit, Mich., a
corporation of Delaware

Application July 23, 1931, Serial No. 552,680

8 Claims. (Cl. 91—65)

This invention relates to the striping of vehicle wheels and has particular reference to a device and method whereby a stripe of a different colored paint may be placed on the wheel of a vehicle.

To paint a stripe on a wheel by hand was found to be too costly and where it is desired to use a stripe for the purpose of improving the appearance of the wheel, it has been found that the device of the present invention has proved of considerable value and has enabled the more ready and quicker application of a stripe and at much less cost.

In carrying out the invention, use is made of two masks which are successively applied to the wheel during the painting operation. Each mask covers the hub of the wheel and has fingers corresponding in number to the spokes of the wheel. When in position on the wheel, the mask and fingers cover the hub and portions of spokes to which it is desired no paint be applied. A coat of the paint is sprayed around the edges of the fingers, the mask then removed and the second mask is then applied and a second spray of coating of paint applied. The second mask is in all respects similar to the first except that the fingers are somewhat larger. After the second mask is removed, a thin stripe or ribbon of paint is left on the wheel.

The mask per se comprises a central dished holder member and a plate resiliently mounted thereon. The edge of the plate extends beyond the holder and is formed into a plurality of sharply pointed fingers which extend out over the spokes of the wheel. The holder has secured thereto a pair of springs for each finger, the ends of the springs extending out and contacting with the fingers at spaced apart points tightly to hold the fingers against the spokes when the mask is in position. A stud or projection on the holder extends into an opening in the wheel and serves to position the mask in a manner that the fingers will be positioned over the spokes.

In the operation, the wheel is mounted on a suitable upright which is also adapted to hold the mask in place.

On the drawings:

Figure 1 is a sectional view through the mask and mounting of the invention showing the parts in operative position, the view being taken substantially on the line 1—1 of Figure 2.

Figure 2 is a side elevation of the portion of a wheel showing the mask in position, the view being taken substantially on the line 2—2 of Figure 1.

Referring to the drawings, the numeral 2 indicates the booth or housing in which the upright 4 is mounted. The booth has the opening 6 at its front, the purpose of which is to allow the insertion and removal of the wheel and to permit

the application of paint to the wheel. The housing has a ventilation opening at 8 to allow the withdrawal of paint fumes.

On the top of the upright 4, there is journaled the head 10 which has the bore 12 and the bushing 14 therein. An oil cup 16 lubricates the bearing surface of the bushing 14. Extending into the bushing 14 is a rotatable axle 18 having the enlarged head 20 for the reception of the hub member 22 of the wheel 24, the spokes of which are indicated at 26. The shaft 18 is bored as indicated at 28 and receives therein the plunger 30, the rear end of which is straddled by the forked double cam member 32 journaled by the pin 34. A handle 36 is used to operate the cam. The plunger 30 has the head 38 which extends into the hollow portion of the securing member 40 having a neck 42 and a head 44, the purpose of which later will be described. The inner portion of the securing member 40 is threaded and receives the hollow nut 46. As shown in Figure 1, the plunger 30 passes through the nut 46 and a spring 48 is confined between one side of the nut and the head 38 while a second spring 50 is confined between the nut and a shoulder 52 in the bored portion 28 of the shaft 18.

The mask of the invention is indicated as a whole at 54 and comprises the holder member 56, the positioning collar 58 and the plate 60 having fingers 62. The holder 56 is hollow or dished as shown in Figure 1 and has the peripheral annular flange 64.

A hook 66 is pivoted as at 68 adjacent the center of the holder and is adapted to swing into and out of engagement with the neck 42 and head 44 as shown in Figure 2 to hold the wheel 24 on the head 20. The dotted line position of Figure 2 shows the position of the hook when it is desired to remove the wheel.

The plate 60 is resiliently secured to the holder 56 by means of a plurality of coil springs 68 mounted in housings 70 secured to the flange 64 of the holder 56. Each housing 70 is secured by means of the rivets 72. Four housings are shown on the drawings but as many as desired may be used. A rivet or stud 74 has an enlarged head 76 which projects into the housing. The shank portion of the stud extends away from the flange 64 and has its end reduced and passes through the plate 60 and is riveted thereto as shown at 77. The springs 68, as shown in Figure 1, are confined between the end of the housing 70 and the head 76 and constantly urge the stud 74 away from the housing. The purpose of this structure is to enable the plate 60 of the mask readily to be positioned on the wheel and to cause the springs 78 and 80 firmly to press the fingers 62 against the spokes 26. The springs 78 and 80 are secured at their ends by means of the rivets 82 to the holder 54 and have their free ends con-

tacting with the fingers at spaced apart points as shown in Figure 1. There are two springs for each finger and as many fingers as there are spokes on the wheel.

5 The wheels 24 are provided with an extra opening 84 in which there is adapted to be received the rubber head 86 of a positioning stud or bolt 88 secured as at 90 to the holder 56. When the head 86 enters the opening 84, each finger 62 and 10 the point 91 thereof will be positioned over a spoke as shown in Figure 2.

The holder 56 is provided with two handles 92 and 94 to assist in the application and removal of the mask 54.

15 In the operation of the device two masks, such as shown at 54, are provided. These masks are identical in structure except that the fingers of one are larger than the fingers of the other, that is, they cover a greater area by an amount sufficient to form a stripe of a desired width. The stripe width in the disclosure of the drawings is indicated by the arrows and the letter A in Figure 2.

The operation of the device is as follows. If 25 the wheels are not already sprayed with the regular wheel color, the operator first sprays at least the center portion of the wheel with the desired color. This spraying may be done while the wheel is on the mount or previously. If the 30 wheel is not already on the mount, it is now positioned on the head 20, the mask 54 placed over the wheel so that the rubber head 86 of the stud 88 is positioned in the opening 84 which will cause the fingers 62 to be positioned as shown in 35 Figure 2. The hook 66 is then thrown from the dotted line position in Figure 2 to the full line position. The lever 36 (Figure 1) is then swung from the full line position to the dotted line position. This will bring the cam into action and 40 cause the plunger 30 to be drawn to the right to pull and resiliently to hold the head 44 against the hook 66 and rigidly to hold the mask and wheel on the head 20. The springs 48 and 50 will be compressed in this operation. The wheel 45 is, of course, capable of being turned to any desired position. It may be rotated with the shaft 18 in the bearing 14, or the wheel and head 10 are rotatable as a unit in the upright 4. When the mask is applied, the springs 78 and 80 will tightly 50 press the fingers 62 against the spokes 26, the mask thereby concealing all of the center portion of the wheel and a portion of the spokes. The operator then turns the paint gun on the wheel adjacent the fingers and gives the wheel 55 a turn which will cause a spraying of the wheel entirely around the mask at the fingers. The mask 54 is then removed and the second mask having the larger fingers is then applied. A second paint gun with a different colored paint is 60 then applied in the same manner to give the regular wheel color. The mask is then removed and there is left a stripe of a width represented by the difference in the size of the fingers of the two masks.

65 Referring to Figure 2, the letter B represents the first color to be applied to the wheel and which is applied prior to the application of either of the masks. This color may correspond to the regular color of the wheel or a different color if desired. The letter C represents the stripe which it is desired to apply to the wheel. The paint of the color of the stripe C is applied when the mask with the smaller fingers is fixed to the wheel. This smaller mask will cover the hub of

the wheel and the spokes to the extent indicated by the lines D. The larger mask in position is shown at E and covers over the painted section B as well as an additional portion of a width of the stripe C. F indicates the final color (which 80 may be the same as the color B) applied after the mask E is in position.

I claim:

1. In a mask for painting spoked wheels, a dished holder adapted to be removably secured over the wheel during the application of paint thereto, a collar secured in the dished portion and adapted to position the mask on the wheel, a plate secured to the holder, and a plurality of fingers on said plate, said fingers covering the 90 portion of the wheel not to be painted.

2. In a mask for painting spoked wheels, a holder adapted to be removably secured on the wheel, a plurality of fingers secured to the holder and adapted to cover the wheel portions not to be 95 painted, and springs secured to the mask and urging said fingers against the wheel.

3. In a mask for painting spoked wheels, a holder adapted to be removably secured on the wheel, a plurality of fingers secured to the holder 100 and adapted to cover the wheel portions not to be painted, and a plurality of springs for each finger urging said fingers against the wheel, said springs secured to the mask.

4. In a mask for painting spoked wheels, a 105 holder adapted to be removably secured on the wheel, a plurality of fingers secured to the holder and adapted to cover the wheel portions not to be painted, and a plurality of springs acting on each finger at spaced points urging said fingers 110 against the wheel, said springs secured to said mask.

5. In a mask for painting spoked wheels, a holder adapted to be removably secured over the 115 wheel side, a plurality of fingers secured to the holder and extending over a part only of the spokes, the fingers corresponding in number to the spokes, and means resiliently urging said fingers against the spokes of the wheel when the mask is in position, said fingers and holder 120 adapted to cover the portion of the wheel not to be painted.

6. In a mask for painting spoked wheels, a holder adapted to be removably secured over the 125 wheel during the application of paint thereto, a plate secured to the holder, a plurality of fingers on said plate and extending over a part only of said spokes, said fingers corresponding in 130 number to the spokes, said fingers and holder covering the portion of the wheel not to be painted, and means resiliently urging said fingers against the spokes when the mask is in position.

7. In a mask for painting spoked wheels, a holder adapted to be removably secured over the 135 wheel during the application of paint thereto, a plurality of pointed fingers connected to said holder and having arcuate sides and adapted to cover the portion of the spokes not to be painted, and means resiliently pressing the points of said 140 fingers against the spokes.

8. In a mask for painting spoked wheels, a holder adapted to be removably secured over the wheel during the application of paint thereto, a plate, means resiliently securing the plate to the 145 holder, and a plurality of fingers with arcuate sides formed on the plate and covering the portion of the wheel not to be painted.
